CLAIM

The ornamental design for a mug with baseball glove, as shown and described.

DESCRIPTION

FIG. 1 is a top perspective view of a mug with baseball glove showing our new design;

FIG. 2 is a top view of the mug with baseball glove;

FIG. 3 is a bottom view of the mug with baseball glove;

FIG. 4 is a front view of the mug with baseball glove;

FIG. 5 is a side view of the mug with baseball glove; and,

FIG. 6 is an enlarged view of the dashed rectangular section shown in FIG. 4.

Where included, the use of stippling is intended to denote a difference in materials.

The broken lines shown in the figures represent portions of a mug with baseball glove that form no part of the claimed design.
